(57) CLAIM

The ornamental design for a shirt, as shown and described.

DESCRIPTION

FIG. 1 is an enlarged front perspective view of a shirt showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof;

FIG. 8 is an enlarged front perspective view of a shirt showing a second embodiment of the design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is an enlarged top plan view thereof; and,

FIG. 14 is an enlarged bottom plan view thereof.

In FIGS. 1-14, the broken lines showing portions of the human figure form no part of the claimed design. The remaining broken lines, on the surface of the shirt represent stitching.
